UNITED STATES PATENT OFFICE.

MARVIN A. BRIGGS, OF PATASKALA, OHIO, ASSIGNOR OF ONE-HALF TO
OLIVER P. CLIFTON, OF SAME PLACE.

CHURN.

SPECIFICATION forming part of Letters Patent No. 278,391, dated May 29, 1883.

Application filed January 9, 1883. (No model.)

To all whom it may concern:

Be it known that I, MARVIN A. BRIGGS, a citizen of the United States, residing at Pataskala, in the county of Licking and State of Ohio, have invented certain new and useful Improvements in Churns; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention pertains to improvements in churning, having for its object to cause the thorough and rapid churning of the cream; and it consists in the combination and arrangement of parts substantially as herein-after more fully set forth.

20 In the accompanying drawings, Figure 1 is a partly sectional and partly side elevation of my improved churn. Fig. 2 is a vertical cross-section on the line *y y* of Fig. 1; and Fig. 3 is a side elevation of the dasher removed from the cream-receptacle.

In carrying out my invention I construct the cream-receptacle A and its affixed underneath water tank or reservoir A' preferably of tin and oblong in shape, and each with a 30 corrugated bottom, as seen at *a a'*, the purpose of which is to prevent kinking of the tin when exposed to the action of cold cream in the receptacle and of the hot water in the tank or reservoir, as has heretofore been caused by the forces of expansion and contraction. The drawing off of the watery particles from the cream afterchurning is facilitated by means of the stoppered opening *b'* at one end of the receptacle A. The receptacle A is suspended 35 in position by means of the bail B, affixed thereto, and is reciprocated by grasping it at *c* and moving it with the hand or otherwise applying motion thereto. I attach importance to the stoppered vent *b* and stoppered opening *d* in the hot-water tank or reservoir, by means of which the hot water can be quickly drawn off to prevent overheating the cream, which is a great practical advantage.

C is the dasher, which has two crossing se-

ries of blades or bars, C', made preferably in 50 practice of galvanized iron, the ends of which are riveted or otherwise fastened to plates C², which plates are fastened to four corner tubes, C³, said tubes being passed through and fastened to a cover, C⁴. The cover C⁴ has at its 55 apex a handle or bail, *e*, by which the top, with the dasher and its other attached or adjunctive parts, may be lifted out of and replaced in the cream-receptacle. The function of the tubes C³ is primarily to conduct air into 60 the cream while being churned and to produce a continuous circulation of air through the cream. The cover C⁴ has also a flange, *f*, depending from its edge and fitting against the inner side of a compound flange, *g*, said 65 latter flange being fastened to or formed with the cream-receptacle body around an opening therein and extended upward therefrom, and then, lapping upon itself, extended downward into the said receptacle a short distance, as 70 seen in Figs. 1 and 2. This depending flange *g* prevents the splashing of the cream up between itself and the cover-flange *f*, and thence out of the churn body or receptacle. Supported at its side edges upon the concaved 75 bottom of the cream-receptacle is a pan or tray shaped vessel, D, to aid in holding the dasher in place.

I claim and desire to secure by Letters Patent—

1. The combination, with a cream-receptacle, of a dasher composed of two series of blades or bars, plates to which said blades are secured at their upper and lower ends, and the four tubes open at their upper and lower 85 ends and secured to the churn-cover, to which said plates are fastened, as and for the purpose set forth.

2. The combination, with a cream-receptacle, of a dasher composed of two series of 90 blades or bars, plates to which said blades are secured at their upper and lower ends, and the four tubes open at their upper and lower ends, and secured to the churn-cover, to which said plates are fastened, the lower end of the 95 dasher being held by a pan or tray, as and for the purpose set forth.

3. The combination of a receptacle, A, having

a corrugated bottom and the compound flange
g, extending upwardly from the receptacle,
and thence lapping upon itself and projecting
into the receptacle as shown, the churn-cover,
5 the dasher consisting of two series of blades
attached thereto, and the tubular corner sup-
ports open at both ends, as and for the pur-
pose set forth.

In testimony whereof I affix my signature in
presence of two witnesses.

MARVIN A. BRIGGS.
